UNITED STATES PATENT OFFICE

FRIEDA ESSMULLER, OF NEW YORK, N. Y.

COVER.

No. 893,469.

Specification of Letters Patent. Patented July 14, 1908.

Application filed February 17, 1908. Serial No. 416,239.

To all whom it may concern:

Be it known that I, FRIEDA ESSMULLER, a citizen of the United States, and a resident of the city of New York, borough of the Bronx, 5 in the county and State of New York, have invented a new and Improved Cover, of which the following is a full, clear, and exact description.

The object of the invention is to provide a 10 new and improved cover for use on bowls, jars, tumblers and like household and culinary vessels, and arranged to fit the mouth of various vessels of different sizes, and to securely hold the cover in place against accident 15 dental displacement.

The invention consists of novel features and parts and combinations of the same, which will be more fully described hereinafter and then pointed out in the claims.

20 A practical embodiment of the invention is represented in the accompanying drawings forming a part of this specification, in which similar characters of reference indicate corresponding parts in all the views.

25 Figure 1 is a sectional side elevation of the improvement; Fig. 2 is a plan view of the same, and Fig. 3 is a sectional side elevation of a modified form of the improvement as illustrated in Figs. 1 and 2.

30 As illustrated in Figs. 1 and 2, the cover A, of glass, porcelain or other suitable material, is provided on its faces with centrally-disposed knobs B and B' and annular seats C, C', the seats on each face being arranged in 35 series, the seats in each series appearing in step form and succeeding series of seats having the steps in ascending and descending shape, as will be readily understood by reference to Figs. 1 and 2. The steps C on one 40 face of the cover A alternate with corresponding steps C' on the other face, so that an exceedingly large number of annular seats are provided to permit of fitting the cover on a large number of vessels of different sized 45 openings or mouths.

As shown in Fig. 3, the cover D is provided on its upper face with a centrally-arranged knob E, and on its under face with annular seats F arranged in two series, the 50 seats in each series appearing in step form and in ascending and descending shape.

From the foregoing it will be seen that by having the seats arranged in the manner described, a very snug fit is had on the mouth of the vessel to be covered, and the cover is 55 securely held in place on the mouth owing to the arrangement of the seats in step form, so that the cover is not liable to accidental displacement.

The cover shown in Figs. 1 and 2 can be 60 used with either face down and as the seats on the opposite faces alternate, it is evident that an extremely large number of seats are provided for engagement with vessels of different sizes.

Having thus described my invention, I claim as new and desire to secure by Letters Patent:

1. A cover for household and culinary vessels having concentric annular seats on its 70 under face arranged in series, the seats in each series being arranged in step form and one series of seats surrounding the other series.

2. A cover for household and culinary vessels having its under face provided with concentric annular seats for engagement with the mouth of the vessel, the seats being arranged in series, and the seats in each series appearing in step form, the seats of one series 75 increasing in diameter in the direction of the top of the cover and the seats of the other series increasing in diameter in the direction of the bottom of the cover.

3. A cover for household and culinary vessels, having a central knob on its upper face, and a plurality of concentric annular seats on its under face arranged in step form, the seats being arranged in series, the seats of one series progressively increasing in diameter 80 from the top seat downward, and the seats of the other series progressively decreasing in diameter from the top seat downward.

4. A cover for household and culinary vessels having each face provided with a central 85 knob, an outer series of concentric annular seats on each face arranged in step form, and concentric annular seats on each face arranged in step form and within the said outer series of seats.

5. A cover for household and culinary vessels, having each face provided with a cen- 100

tral knob and concentric annular seats arranged in step form, the seats of one face being positioned at radial distances from the common center of the two faces which alter-
5 nate in length with the radial distances of the seats on the other face.

In testimony whereof I have signed my

name to this specification in the presence of two subscribing witnesses.

FRIEDA ESSMULLER.
